UNITED STATES PATENT OFFICE.

IRVIN ROSENFIELD, OF NEW YORK, N. Y., ASSIGNOR OF ONE-HALF TO CHARLES GUSTAV WIRTHS, OF WOODHAVEN, NEW YORK.

CHANGE-MAKING MACHINE.

970,557.

Specification of Letters Patent. Patented Sept. 20, 1910.

Application filed April 30, 1909. Serial No. 493,072.

To all whom it may concern:

Be it known that I, IRVIN ROSENFIELD, a citizen of the United States, residing at New York city, Bronx, county and State of New York, have invented new and useful Improvements in Change-Making Machines, of which the following is a specification.

This invention relates to a machine of novel construction for delivering any desired amount of change, up to one dollar, without requiring mental calculation to ascertain the aggregate value of the different pieces of coins released. The machine is provided with preferably one hundred keys marked successively from 1 to 100, and so connected to the ejecting mechanism that by depressing any one of said keys, the amount of change indicated thereon will be liberated. In this way the manipulation of the machine is facilitated and errors, owing to miscalculation, are prevented.

In the accompanying drawings: Figure 1 is a front elevation of my improved change making machine; Fig. 2 a vertical longitudinal section on line 2—2, Fig. 1; Fig. 3 a longitudinal section on line 3—3, Fig. 2, showing the sliding plates partly broken away; Fig. 4 a cross section on line 4—4, Fig. 2; Fig. 5 a vertical section of the first penny magazine; Fig. 6 a similar section of the second penny magazine; Fig. 7 a cross section on line 7—7, Fig. 5, and Fig. 8 a similar section on line 8—8, Fig. 5.

The frame 10 of the machine is preferably so supported upon legs 11, as to have a rearward dip. At its front, frame 10 is provided with preferably seven coin magazines 12, 13, 14, 15, 16, 17, 18, of which magazines 12, 13 are both adapted for the reception of stacks of one-cent pieces; magazine 14 is adapted for the reception of nickels; magazines 15 and 16 are both adapted for dimes, while magazines 17, 18 are adapted for quarters and half-dollar pieces, respectively. The coins are supported within each magazine upon a base plate or rest 19 having a concave front edge over which the coins are adapted to be pushed, by the mechanism hereinafter described, so as to fall into a chute 20 that extends in front of all the magazines and discharges all the coins simultaneously released, through a common outlet 21.

The means for ejecting the coins consist

of preferably eight spaced superposed plates 55 22, 23, 24, 25, 26, 27, 28, 29, arranged parallel to each other and having a slight rearward dip. The plates are of rectangular shape and are slidably supported upon pins 30 projecting inwardly from posts 31 secured to the inner sides of the machine frame. Each plate is provided at its forward end with a flat finger or ejector marked respectively 32, 33, 34, 35, 36, 37, 38, 39, such ejector entering one of the magazines 12 to 18, with the exception of ejectors 32 and 33, which both enter magazine 12. That is to say, ejector 32 of plate 22, as well as ejector 33 of plate 23, both enter the first penny magazine 12 through a slot formed in the back wall thereof directly above its base plate 19. Ejector 32 is superposed upon ejector 33, while the latter, in turn, moves along the base plate 19 of the magazine. Each of these ejectors is of a thickness adapted for the ejection of a single coin, so that when ejector 33 is advanced, a single penny is discharged, while when both ejectors are advanced, two cents are simultaneously discharged. In order to hold back the coin aligned with top ejector 32, when a single penny only is delivered by ejector 33, said top ejector is provided with a curved claw 40 that partly encompasses its coin, but will release the same upon the advance of ejector 32. Ejector 34 of plate 24 enters magazine 13 directly above its base plate 19, and in like manner ejectors 35, 36, 37, 38, 39 enter, respectively, the magazines 14, 15, 16, 17, 18. As will be readily understood, the several coin ejectors (with the exception of the superposed ejectors 32, 33) are arranged side by side, each ejector entering one of the magazines while clearing all the other magazines. The thickness of each ejector is such that it will engage a single coin, with this exception, that ejector 34 is of double thickness, so that it will simultaneously discharge two cents. As plates 22 to 29 are arranged above one another, and as the ejectors extend forward from their respective plates, such ejectors will assume a step-shaped relation and the base plates of the various magazines along which the ejectors move, are correspondingly stepped, (Figs. 1 and 4.)

To prevent all, excepting the bottom coins, from being pushed out of the magazines, the

partitions 41 between the latter are provided along their upright edges with laterally extending flanges 42 notched at their bottom as at 43.

5 In order to actuate plates 22-29, there are employed, preferably, one hundred keys 44, each of which is designed to deliver a different amount of change from one cent up to one hundred cents, so that by manipulating the proper key, the change desired will be obtained. The keys are preferably arranged in ten parallel rows, each containing ten keys, and each key has a finger-piece bearing a character which indicates the 15 amount of change it will eject. Each key is made in the form of a two-arm lever, the ten keys of every transverse row being fulcrumed upon a common shaft 45 extending across frame 10, so that for the ten rows 20 of keys, ten shafts 45 are employed. The keys of every row are separated from each other by spacing collars 46 mounted on their shaft 45, and tightened up by a coiled spring 47. The relative arrangement of the keys is 25 such, that those mounted on any one shaft are staggered with those mounted on the adjoining shafts, by which arrangement space is economized and an increased sweep for the key is obtained. It is preferred to 30 hang each key in such a manner upon its shaft 45, that it can be readily removed therefrom; for which purpose it is provided with a fork 48 straddling such shaft. Fingers 49 extending forwardly from the upper 35 arms of the nine rear rows of keys 44, find a bearing on the collars 46 of the immediately preceding rows and thus support the keys in their normal position. The keys of the front row are similarly sustained by an 40 abutting flange 50 of frame 10.

Each of the keys 44 operatively engages those specific plates 22 to 29 which jointly or severally eject the quantity of change indicated upon the finger-piece of said key. 45 To this effect, the lower arm of each lever 44 extends through the entire number of plates 22 to 29, which are slotted for the accommodation of said arm. The slots in plates 22-29 are made in two different 50 lengths, shorter slots 51 being provided for those levers which are to take the plates along, while longer slots 52 are provided for those levers which are to clear the plates. The position of the short slots 51 is such 55 that their front perimeters are in substantial contact with the forward edges of the keys, so that on tilting the latter, the plates will be taken along, to eject the coins. The length of the short slots should be such that 60 there is provided a sufficient clearance between their rear perimeters and the rear edges of the unoperated keys to hold the latter in an inert position when the plates are advanced by the action of keys of a different denomination. The long slots 52 ex-

tend to such a distance in front and back of their respective keys, that the latter have a free play therein without coming into contact with either the front or rear perimeters of the slots. Or in other words, there is in 70 all positions of the keys a clearance between such keys and the plates wherever the latter are provided with the long slots. While plates 22-29 are advanced by means of the keys 44, they are retracted by coiled springs 75 53 hooked at one end to frame 10, as at 54, while at their other end they are adjustably secured to their respective plates by means of racks 55 that permit the tension of the springs to be adjusted. As has been stated, 80 the correlation of the parts is such, that each key will take along such specific plate or plates only, as will deliver the change indicated upon the finger-piece of such key. It has also been set forth that this taking 85 along is effected by the engagement of the keys with the perimeters of the short slots 51, while the keys will move idly within the long slots 52. To illustrate: The one cent key actuates solely plate 23 of the lower 90 penny ejector 33; the two cent key actuates plate 24 of the two cent ejector 34; the three cent key actuates, simultaneously, plates 23 and 24, and the four cent key actuates, simultaneously, plates 22, 23 and 95 24. The fifteen cent key 44^a will actuate the five cent plate 25 and the ten cent plate 27, while it will pass loosely through all of the other plates. The thirty-five cent key 44^b will engage the ten cent 100 plate 27 and the twenty-five cent plate 28. The fifty-five cent key 44^c will actuate the five cent plate 25 and the fifty cent plate 29. In like manner the twenty cent key will engage both plates 26, 27 to simultaneously 105 discharge two dimes, while the dollar key will simultaneously discharge one nickel, two dimes, one quarter and one half dollar piece, as will be readily understood. It will thus be seen that by depressing the proper 110 key, the operator will readily obtain the change desired without making any mental calculation.

It is preferred to mount the coin containing magazines in an upright position, while 115 the ejectors, as well as the base plates of said magazines, have a slight rearward dip. By this construction the coins within the magazines will assume a corresponding dip and will not be apt to jam against the rear walls 120 of the magazines during the retraction of the ejectors and the resulting descent of the coin stacks.

I claim:

1. In a change making machine, a series of 125 coin magazines combined with a corresponding series of superposed slotted slidable plates extending back of the entire series of said magazines, a series of coin ejectors on the plates which are arranged side by side 130

and are adapted to separately enter different magazines, a series of key levers passing through said plate series and adapted to operatively engage a selected number of said plates, while clearing the other plates.

5 2. In a change making machine, a frame, a series of parallel shafts supported thereby, a series of spaced keys fulcrumed to the shafts in staggering relation with each

10 other, collars mounted upon the shafts intermediate the keys, a series of superposed apertured plates engaged by the keys and having coin ejectors, and coin magazines adapted to receive said ejectors.

15 3. In a change making machine, a frame, a series of parallel shafts supported thereby, a series of spaced keys fulcrumed to the shafts in staggering relation with each other and having forwardly extending fingers, col-

20 lars mounted upon the shafts intermediate the keys and adapted to be engaged by said fingers, a series of superposed apertured plates engaged by the keys and having coin

ejectors, and coin magazines adapted to receive said ejectors.

25

4. In a change making machine, a frame, a series of parallel shafts supported thereby, a series of keys having forks adapted to straddle said shafts, a series of superposed apertured plates engaged by the keys and having coin ejectors, and coin magazines adapted to receive said ejectors.

5. A change making machine, comprising a series of coin magazines having stepped coin rests, a series of superposed, slidable 35 and apertured plates having correspondingly stepped ejectors adapted to enter the magazines above said coin rests, and keys operatively engaging the plates.

Signed by me at New York city, (Man- 40
hattan,) N. Y., this 29th day of April, 1909.
